WHEEL

Roy E. Richter, Downey, Calif., assignor to Bell Auto
Parts, Inc., Bell, Calif., a corporation of California

Filed Aug. 10, 1964, Ser. No. 81,215

Term of patent 14 years

(Cl. D14—30)

FIG. 1.

FIG. 2.

FIG. 4.

FIGURE 1 is a front elevation of the wheel showing my new design;

FIGURE 2 is a rear elevation; and

FIGURE 3 is a sectional view taken along lines 3—3 in FIGURES 1 and 2.

FIGURE 4 is a perspective.

The dominant features of my design reside in the portions shown in full lines.

I claim:

The ornamental design for a wheel, substantially as shown and described.
